KITE

Harold A. Levine, 165 Dwight St., New Haven, Conn.

Filed Mar. 28, 1962, Ser. No. 69,460

Term of patent 14 years

(Cl. D34—15)

FIGURE 1 is a perspective view of a kite embodying my new design as viewed from the ground when such kite is in flight.

FIGURE 2 is a plan view of the novel kite of FIGURE 1 illustrating the top side thereof.

FIGURE 3 is a front elevation view thereof.

The characteristic features of my design reside in the combination, on the bird kite, of the flat triangular head portion, with the contrastingly colored arcuate wing flaps, all as shown.

I claim:

The ornamental design for a kite, as shown and described.
